(57) **CLAIM**

The ornamental design for a jump rope with handles, as shown and described.

DESCRIPTION

FIG. 1 is a perspective view of a jump rope with handles; FIG. 2 is a left side view of the jump rope with handles of FIG. 1;

FIG. 3 is an opposite right side view of the jump rope with handles of FIG. 1;

FIG. 4 is a top plan view of the jump rope with handles of FIG. 1;

FIG. 5 is a bottom plan view of the jump rope with handles of FIG. 1;

FIG. 6 is a first end view of the jump rope with handles of FIG. 1; and,

FIG. 7 is an opposite second end view of the jump rope with handles of FIG. 1.

All the broken lines on the jump rope with handles form no part of the claimed design and the broken away symbols in the drawings indicate the appearance of any portion of the article between the break lines forms no part of the claimed design.

1 Claim, 4 Drawing Sheets
